COMBINATION TIMBER CRUISING AND RANGE POLE

Sam Coumbs, 2604 N. Lee, Spokane, Wash. 99207

Filed Mar. 12, 1973, Ser. No. 340,580

Term of patent 14 years

Int. Cl. D10—05

U.S. Cl. D88—1

FIG. 1 is a side elevation view of a combination timber cruising and range pole;

FIG. 2 is an enlarged fragmentary perspective view showing the top end of the device in FIG. 1;

FIG. 3 is an enlarged perspective view looking down on the lower end of the device shown in FIG. 1;

FIG. 4 is an enlarged top view of the device shown in FIG. 1; and

FIG. 5 is an enlarged bottom view of the device shown in FIG. 1.

I claim:

The ornamental design for a combination timber cruising and range pole, as shown and described.
